UNITED STATES PATENT OFFICE.

JOHN H. RUSSELL, OF BOSTON, MASSACHUSETTS.

HAIR-PIN.

SPECIFICATION forming part of Letters Patent No. 356,263, dated January 18, 1887.

Application filed February 24, 1885. Serial No. 156,844. (Model.)

To all whom it may concern:

Be it known that I, JOHN H. RUSSELL, of Boston, county of Suffolk, State of Massachusetts, have invented an Improvement in Hair-Pins, of which the following description, in connection with the accompanying drawings, is a specification, like letters on the drawings representing like parts.

The object of my invention is to produce a hair-pin which will hold the hair of the user securely, and will be itself more securely retained in the hair than the hair-pins now commonly in use.

The hair-pin forming the subject of this invention consists of two prongs, each of which, about midway of its length, is curved toward and crosses the other, thus forming a closed loop at the upper end of the hair-pin, where the two prongs unite. The prongs below the crossed or intersecting point are curved outward, so that when inserted in the hair they receive a larger portion of the hair between them than they would if parallel with one another. The two prongs normally are in contact or nearly in contact with one another at their point of intersection, but, owing to the elasticity of the wire, will spring away from one another or yield to permit the hair to pass between them and into the closed loop that is formed at the upper end of the pin, or between the junction and point of intersection of the prongs.

Figure 1 is an elevation of a hair-pin embodying this invention, and Fig. 2 a diagram showing the position the prongs assume in being inserted into the hair.

The pin is shown as made from a piece of wire, bent around nearly one hundred and eighty degrees, as shown at *a*, forming two prongs, *b c*, each of which, near the middle of its length, is curved toward the other, as shown at *d*, so that the prongs cross or intersect one another, as shown at *e*, and beyond the point of intersection they are curved again, as shown at *f*, nearly to their former direction. The ends of the prongs are preferably flared or curved outward, as shown at *g*, so that they are more widely separated at their extreme ends than in the main portion of their length.

The position of the two prongs *b c* with relation to one another is thus reversed above

and below the point of intersection at *e*, and the two prongs rest in contact with one another, or nearly so, at the point *e*.

In using the pin it is first inserted in the hair up to the point of intersection, (marked *e*), when that portion above the point of intersection remaining between the thumb and finger must be turned half round (either to the right or left, as the prongs happen to be crossed) to facilitate the passing of the prongs their whole length into the hair.

It will be observed that the prongs by this turn are made more nearly parallel, as shown in Fig. 2, and that the points marked *g*, instead of flaring away, are made to converge toward each other. By this means, in the second half of the passage of the pin into the hair, or that portion of the passage which takes place after the turn is made, the ends of the prongs gradually converge until they meet, or nearly so, when the pin is completely inserted.

The elasticity of the wire of which the pin is composed is sufficient to draw the two prongs toward and into contact with one another, or nearly so, after it is inserted in the hair, thus retaining a portion of the hair securely held in the closed loop above the intersection, and the remaining portion of the hair is securely held between the lower portion of the said prongs. The pin thus not only holds or fastens the hair that is engaged between its prongs throughout their entire length, but is itself securely retained in the hair, and is not likely to drop out or become detached therefrom until positively withdrawn by the user.

I do not claim a hair-pin in which either or both of the legs or prongs are curved spirally, so as to be screwed into the hair, as such construction is not new; but I limit my invention to a hair-pin in which the legs are crossed angularly and are sprung apart in operation, as herein shown and described.

I claim—

1. As an improved article of manufacture, a hair-pin composed of a single piece of wire bent at or near its middle to form two prongs, that extend thence in curved planes and intersect at or near their middle, substantially as described.

2. A hair-pin composed of a single piece of wire bent at its middle to form two prongs,

which cross each other, and each of which extends in two nearly similar curves from its middle toward its point and toward its junction with the remaining prong, respectively, 5 substantially as described.

3. A hair-pin composed of a single piece of wire bent to form prongs, each of which is bent at a point near its middle, and extends thence toward its end and junction with the remaining prong, respectively, in continuous similarly-curved planes, whereby when said prongs

are crossed the opposite ends thereof shall be curved toward and from each other, respectively, as and for the purpose specified.

In testimony whereof I have signed my name 15 to this specification in the presence of two subscribing witnesses.

JOHN H. RUSSELL.
